UNITED STATES PATENT OFFICE.

SAMUEL HOUGH, OF ATCO, NEW JERSEY.

AERIAL BOMB.

1,394,902.

Specification of Letters Patent. Patented Oct. 25, 1921.

Application filed July 9, 1919. Serial No. 309,761.

To all whom it may concern:

Be it known that I, SAMUEL HOUGH, a citizen of the United States, residing at Atco, in the county of Camden and State 5 of New Jersey, have invented new and useful Improvements in Aerial Bombs, of which the following is a specification.

My invention relates to a new and useful improvement in aerial bombs, and has for 10 its object to so construct a bomb of this description as to adapt it for release from a flying machine or other source at a height above the object to be destroyed and cause it to fall through the air in an upright position.

A further object of my invention is to provide for the cushioning of the explosive in such manner that the bomb may be readily handled for shipment and the like without 20 danger of accidental discharge.

A still further object of my invention is to so surround the explosive with shrapnel bullets that when the explosion takes place there will be a tendency to project the majority of these bullets at a downward angle.

With these ends in view, this invention consists in the details of construction and combination of elements hereinafter set forth and then specifically designated by the 30 claims.

In order that those skilled in the art to which this invention appertains, may understand how to make and use the same, I will describe its construction in detail, referring 35 by numerals to the accompanying drawings forming a part of this application, in which:—

Figure 1, is an elevation of my improved bomb partly broken away and sectioned so 40 as to fully illustrate the construction thereof.

Fig. 2, is a section at the line 2—2 of Fig. 1, and

Fig. 3, is a section at the line 3—3 of Fig. 1.

In carrying out my invention as here embodied, 1 represents the outer casing which is bulged or enlarged near the bottom thereof as indicated at 2 and this casing is closed at the top with the head 4 and at the bottom 50 by the head 5 annular grooves being formed in the heads for the reception of the edges of the casing as indicated at 6.

The head 4 is provided with a hub 7 which is threaded for the reception of the 55 upper end of the tube 8 while the head 5 is also provided with a similar hub 9 which

is threaded for the reception of the lower end of the tube 8, and the screwing of these hubs into the end of the tube 8 will assemble the device holding the heads securely upon the casing 1 as will be readily understood.

The space between the tube 8 and the inner walls of the casing 1 serves as a container for the shrapnel bullets 10 and as 60 will be seen from the drawing a larger percentage of these bullets lie within the enlargement 2 of the casing thus giving increased weight to the lower portion of the bomb so that in falling this increased weight 65 and the lower end will cause the bomb to remain vertical while falling.

11 represents the explosive container which is preferably of cylindrical form and is suspended within the tube 8 by the coil 70 spring 12 attached to the upper end thereof and to the hub of the head 4. This form or suspension for the explosive container permits a gentle movement of said container instant to the handling of the bomb, but 75 prevents shocks or sharp vibrations from reaching it.

The lower end of the container 11 is provided with a neck 13 through which the container may be filled with the explosive and this neck is connected by a rubber or other flexible tube 14 to the nipple 15 threaded through the partition 16 which latter is threaded into the lower end of the tube 8. This arrangement while permitting the container 11 to have a slight swinging movement in all directions holds it approximately in the center of the tube 8 and the partition 16 divides off and forms a chamber in the major portion of the tube 8 90 which chamber is filled with any suitable gelatin substance which will serve to stabilize the container 11 and at the same time prevent its radical displacement affording a cushion to said container which will absorb external shocks and jars and overcome any tendency to explode or detonate.

17 represents the detonating cartridge which is fitted within the lower end of the nipple 15 and there held by the ring 18 105 which latter is secured to the partition 16.

19 represents the firing pin which passes through the cap 20 threaded upon the nipple 21 which in turn is threaded into the hub 9 and this firing pin has a shoulder 22 which 110 limits its retraction, the spring 23 bearing upon the pin 24 serving to normally hold

the pin in the position shown in Fig. 1, or in its retracted position.

25 represents the firing plug which passes into the nipple 21 having its movements 5 therein limited by the screw 26 which latter is threaded through the boss 27 formed upon the head 5 and projects into a groove 28 formed lengthwise of the firing plug. Thus while the firing plug may not be withdrawn 10 until the screw 26 is removed yet it has a limited sliding movement. This firing plug 25 carries a shoe 29 which is intended to contact with the ground or any other object upon which the bomb may fall and when so 15 contacting will be forced upward driving the firing plug into contact with the firing pin 19 which in turn being forced against the cap of the cartridge 17 firing said cartridge and in consequence thereof exploding 20 the charge in the container 11. This exploding of the charge will burst the bomb scattering the shrapnel bullets over a wide range it giving the majority of said bullets a 25 sliding downward angle which will make them most effective when falling upon buildings and the like.

While the gelatin like material contained within the tube 8 surrounding the explosive container may be of inert material and have 30 no active part in the destructiveness of the bomb, yet I prefer that this gelatin matter may be charged with such chemicals as will cause it to ignite and when scattered carrying it in the form of fire or burning particles 35 and that it may also give off deadly gases.

In order that the bomb may be made safe before handling and shipment, I provide a locking screw 30 which is threaded through the boss 27 into a recess or spot formed in 40 the firing plug 25 so that when this screw is in place in this spot the firing pin can not be operated to discharge the bomb or just prior to the bomb being out in action this screw is backed so as to free the firing plug 45 for its intended function.

31 is a ring anchored in the head 7 for suspending the bomb prior to its being dropped from a flying machine or other source.

Of course I do not wish to be limited to 50 the exact details of construction as herein shown as these may be varied within the limits of the appended claims without departing from the spirit of my invention.

Having thus fully described my invention, 55 what I claim as new and useful is:—

1. In a bomb of the character described an outer casing, a tube located in said casing in such manner as to form a compartment between the casing and said tube, a head 60 threaded into each end of the tube, each

head having an annular groove therein for the reception of the ends of the casing, a spring suspended container located within the tube, and means for flexibly connecting the interior of the container with the outside 65 of the tube.

2. An aerial bomb comprising a casing having an enlargement near the bottom thereof, a head fitted to each end of the casing so as to inclose the same, a tube passing 70 through the center of the casing, and threaded to each of the heads, shrapnel bullets filling the space between the inner walls of the casing and the outer walls of the tube, a partition secured in the lower portion of the 75 tube, the explosive container suspended within the tube and the partition, a gelatin mass within the tube surrounding the container, and means for exploding the contents of the container.

3. In a bomb of the character described, an outer casing having an enlargement around the lower portion thereof, a tube occupying the central portion of the casing in such manner as to form a receptacle for 80 shrapnel bullets and the explosive container located within the tube, a spring for suspending said container, a cartridge holder, means for flexibly connecting the lower end of the container with said cartridge holder, 85 a firing pin, means for normally holding said firing pin in its retracted position, a firing plug, a contact shoe carried by said plug, and means for limiting the movement of said 90 firing plug.

4. A bomb of the character described, an outer casing forming a receptacle for shrapnel bullets, said casing having an enlargement near its lower portion so as to increase 100 its holding capacity for said bullets at that point, a tube located within the casing so as to form a chamber therein, an explosive container located within said chamber partly above the enlargement in the casing, a coil spring for suspending said container, a cartridge holding, and flexible means for connecting said container with said cartridge 105 holder.

5. In a device of the character stated, a casing, a head for each end of said casing, a 110 tube within said casing concentric therewith, the ends of said tube being attached to the heads, a partition within said tube adjacent one end thereof, and an explosive container suspended within the tube with its walls 115 normally spaced from the walls of the tube.

In testimony whereof, I have hereunto affixed my signature.

SAMUEL HOUGH.
